UNITED STATES PATENT OFFICE.

CLARENCE C. LONGARD, OF HALIFAX, NOVA SCOTIA, CANADA.

INTERNAL-COMBUSTION ENGINE.

1,109,999.

Specification of Letters Patent.

Patented Sept. 8, 1914.

Application filed November 24, 1913. Serial No. 802,667.

To all whom it may concern:

Be it known that I, CLARENCE C. LONGARD, citizen of Canada, residing at Halifax, in the Province of Nova Scotia and Dominion of Canada, have invented new and useful Improvements in Internal-Combustion Engines, of which the following is a specification.

My present invention has to do with internal combustion engines of the two cycle type; and it consists in the peculiar and advantageous engine hereinafter described and definitely claimed.

In the accompanying drawings: Figure 1 is a vertical diametrical section of an internal combustion engine constituting one practical embodiment of my invention. Fig. 2 is a similar view illustrative of another construction embodying my invention.

The engine shown in Fig. 1 comprises a cylinder and a piston together with an auxiliary piston; the cylinder being divided by the piston 1 into an explosion chamber 2 and a compression chamber 3, and the auxiliary piston 4 being arranged and movable in the explosion chamber, intermediate the piston 1 and the inner end of the explosion chamber. The explosion chamber is provided at 5 with a spark plug or any other suitable ignition device, and is also provided at 6 with an exhaust port, and at 7 with an explosive-mixture inlet port, said port 7 being arranged in communication with the inner end of the explosion chamber, while the port 6 is disposed so as to be in registration with an opening 8 in the upwardly extending wall 9 of the piston 1 during the completion of the outward traverse of said piston. It will also be noted here that the said wall 9 of the piston 1 is provided at 10 with a port designed to communicate during the completion of the inward traverse of the piston 1 with the ignition port or chamber 5. The fuel-inlet port 7 is controlled by an inwardly opening valve 11 which is closed and yieldingly held closed by a spring 12.

At 13 the compression chamber is provided with a port designed to be connected with a carburetor or other suitable source of fuel supply, and leading from the compression chamber at the point 14 to the port 7 is a fuel conduit 15. This conduit is preferably, though not necessarily, formed in the wall of the cylinder, and the cylinder

is also provided by preference with a water jacket 16 as illustrated.

Formed in the auxiliary piston 4 is a port 16* in communication with the portions of the explosion chamber at opposite sides of the said auxiliary piston, and fixed in said port 16* are perforated metallic diaphragms 17, designed to prevent what is commonly called "back firing." The port 16* is controlled by a valve 18, arranged to seat in a direction away from the main piston 1; the said valve being yieldingly held against its seat by a spring 19.

With the understanding that no unburnt explosive mixture is admitted to the explosive chamber until the main piston 1 has made its full outward stroke and the products of combustion of the previous explosion have escaped through the registered parts 6 and 8, the operation of the embodiment described will be fully understood from the following:

When on the inward stroke of the main piston 1, the explosive mixture back of the auxiliary piston 4 has compression sufficient to overcome the spring pressure on the valve 18 in the auxiliary piston 4 which takes place after the exhaust port is closed by the main piston. It is then the valve 18 opens and admits explosive mixture to the chamber between the two pistons. It is this that prevents the escape of unburnt explosive mixture through the exhaust port 6. It will also be manifest that when the charge between the two pistons is ignited, and the main piston is forced outwardly, the unburnt explosive mixture from the compression chamber or crank chamber 3 will be utilized to force the auxiliary piston 4 outwardly against the products of combustion between the two pistons. Then on the inward stroke of the main piston 1 the operation described is repeated. From this it follows that I utilize the auxiliary piston 4 to divide the unburnt explosive mixture from the gases resulting from an explosion of fuel in the chamber between the two pistons.

It will also be gathered from the foregoing that the free passage of explosive mixture between the compression chamber and the explosion chamber assures the supply of a full charge of explosive mixture to the portion of the explosion chamber between the two pistons. This will be ap-

- preciated as an important advantage when it is stated that in the ordinary two-cycle engine the fuel port opens and closes so quickly that when it is attempted to increase the speed of the engine, the explosion chamber is not fully charged before said port is closed. Again it will be observed that the auxiliary piston is operated by the compressed explosive mixture from the compression chamber which acts against the whole surface of the auxiliary piston and exerts great pressure thereon, and thereby increases the propelling force of said auxiliary piston.
- 15 In the port of the auxiliary piston a series of apertured screens is employed with a view to preventing back firing.

In order to cushion the auxiliary piston, I provide the wall 9 of the main piston 1, in combination with an annular recess 21 formed at the outer end of the auxiliary piston and designed to snugly receive the said wall 9 when the pistons come together. I also prefer to employ similar means for cushioning the auxiliary piston on the inward movement thereof, *i.e.*, I provide the said auxiliary piston with an annular extension 22 designed to enter and snugly move in an annular recess 23 formed in the head 30 of the cylinder.

The embodiment shown in Fig. 2 is similar to that shown in Fig. 1 as regards the inlet port 13 of the compression chamber or crank case 3, the conduit 15, the port 7, and the valve 11, equipped with spring 12; also, as regards a chamber 5 to receive a spark plug, and the exhaust port 6, arranged to be uncovered by the main piston when the latter is in its outermost position. The auxiliary piston 4^a differs from the piston 4 of Fig. 1 in that it has no valve-controlled port similar to the port 16^x of the piston 4.

In lieu of the valve-controlled port 16^x of Fig. 1, I provide the embodiment of Fig. 2 with a by-pass port 16^w that connects the chamber back of the auxiliary piston 4^a with the chamber between the two pistons, and is controlled by the valve 18^w and is equipped with foraminous screens 17^w for the purpose hereinbefore ascribed to the screens or diaphragms 17 of Fig. 1.

The operation of the embodiment shown in Fig. 2 is generally similar to that ascribed to the embodiment shown in Fig. 1; the valve 18^w opening and admitting gas into the chamber between the pistons when on the inward stroke of the main piston and when the explosive mixture back of the auxiliary piston 4^a has sufficient compression to overcome the explosive pressure, and the auxiliary piston commences to move down on the products of combustion.

Having described my invention, what I claim and desire to secure by Letters-Patent, is:

1. In an internal combustion engine, a cylinder, a main piston and an auxiliary piston; the cylinder being divided by the main piston into an explosion chamber and a compression chamber and having an inlet port for explosive mixture communicating with the compression chamber and further having an inlet port communicating with the chamber back of the auxiliary piston and an exhaust port communicating with the chamber between the pistons, a conduit intermediate the compression chamber and the port that communicates with the chamber back of the auxiliary piston, non-return means controlling said conduit, a port for leading explosive mixture from the chamber back of the auxiliary piston to the chamber between the pistons, and non-return means for controlling said port. 80

2. In an internal combustion engine, a cylinder, a main piston and an auxiliary piston; the cylinder being divided by the main piston into an explosion chamber and a compression chamber and having an inlet port for explosive mixture communicating with the compression chamber and further having an inlet port communicating with the chamber back of the auxiliary piston and an exhaust port communicating with the chamber between the pistons, a conduit intermediate the compression chamber and the port that communicates with the chamber back of the auxiliary piston, non-return means controlling said conduit, a port for leading explosive mixture from the chamber back of the auxiliary piston to the chamber between the pistons, non-return means for controlling said port, and apertured means in said port for preventing back firing. 95

3. The combination in an internal combustion engine, of a cylinder having an exhaust port and an ignition chamber, a main piston movable in the cylinder and having an inward extension in which is an aperture to register with the exhaust port and another aperture to register with the ignition chamber, and an auxiliary piston arranged in the cylinder and having an annular recess to receive said extension of the main piston and also having an end extension of its own adapted to snugly enter a recess in the cylinder. 100

In testimony whereof I have hereunto set my hand in presence of two subscribing witnesses.

CLARENCE C. LONGARD.
